H. G. ALLEN

CLINCHER FOR WIRE STAPLING MACHINES

Filed July 17, 1926

UNITED STATES PATENT OFFICE.

HOWARD G. ALLEN, OF NIAGARA FALLS, NEW YORK, ASSIGNOR TO MORRISON STITCHER CORPORATION, OF NIAGARA FALLS, NEW YORK, A CORPORATION OF NEW YORK

CLINCHER FOR WIRE-STAPLING MACHINES.

Application filed July 17, 1926. Serial No. 123,221.

This invention relates to the clincher of a stapling or stitching machine whereby staples or stitches of wire are applied to pamphlets, books and the like for holding or binding together the several parts or pages which are to be connected.

It is well known that when driving the legs of a wire staple through a thick pad of paper or other material these legs do not always travel in straight lines and often come out at different distances from the center line of the staple and the ends of these legs are often clinched so that they are arranged at an angle to the center line of the staple and therefore produce an unfinished and unsightly appearance. This is due to conditions heretofore beyond the control of the stapling or stitching machine, such as uneven reeling of the wire on the spool or coil and the quality of the wire, all of which produce a variation in the driving capacity of the wire staple. Experience also shows that the straightness with which wire will be driven depends a great deal on the condition of the knives which sever the wire in lengths suitable for making the staples, inasmuch as the knives when dull produce either a bevel or frayed cut and this causes the legs of the staple when passing through a pad of material to leave off to one side of the center of the staple.

Heretofore each of the clincher blocks in stapling machines has only been provided on its face with one longitudinal guide groove the walls or sides of which are inclined or beveled and this groove served to direct the point or end of a staple leg after it passed through the pad of material toward the center line of the staple with the result that often the staple ends would be inclined or arranged obliquely or twisted out of shape and therefore lacked neatness in appearance.

It is the object of this invention to provide a clincher for stapling machines which will cause the ends or points of the legs after passing through the material to be clinched or bent against the material in a direction parallel with the center line of the staple and thus present a better appearance.

To that end this invention consists in providing each block of the clincher with a plurality of guide grooves any one of which is adapted to receive the point or end of a

staple leg and bend the same parallel with the center of the staple.

In the accompanying drawings:

Figure 1 is a top plan view of a clincher embodying one form of my invention.

Figure 2 is a side elevation thereof with one side plate or wall of the clincher box removed.

Figure 3 is a vertical section taken on line 3-3 of Figure 2.

Figure 4 is a vertical cross section, on an enlarged scale, of one of the clincher blocks or jaws provided with three guide grooves corresponding to Figures 1 and 3.

Figure 5 is a vertical longitudinal section of a pad of material and the staple driving and clinching mechanism of a stapling machine in elevation showing the manner of driving the legs of a staple through a pad of material and turning over or bending the legs against the material in accordance with my invention.

Figures 6, 7, 8 and 9 represent fragmentary bottom views of a pad showing the manner in which the ends or points of the staple legs are bent or turned parallel with the center of the staple by the use of my invention.

Figures 10, 11 and 12 are vertical cross-sections through a pad and a clincher block showing the manner in which the points or ends of the staple legs are turned into parallelism with the center of the staple corresponding to the position of the parts shown in Figures 6, 7 and 8.

Figures 13, 14 and 15 are bottom views showing different forms of the staple ends relative to the center of the staple when applying the same to material by the means heretofore employed.

Figure 16 is a vertical section similar to Figure 4 but showing five guide grooves on the face of the clincher block.

Similar characters of reference indicate like parts on the several views of the drawings.

Although this invention is applicable to machines for stapling or stitching together two various kinds of materials by means of wire staples the same is shown in the drawings in connection with a pad or pile of superposed sheets or layers 20 which are connected by a U-shaped wire staple having its legs 21, 21 passing through this pad, a

cross bar 22 connecting the upper or rear ends of said legs and engaging the rear or upper side of this pad, and two points, ends or toes 23, 23, arranged at the lower or front ends of the legs and bent or turned against the under or front side of the pad, as shown in Figure 5.

The staple driving mechanism may be of any suitable construction and is represented generally in the drawings by the vertically movable driver or hammer 24 which is adapted to engage with the cross bar of the staple and push or force its legs through the pad of material until the cross bar rests against the rear or top side of the pad as shown in Figure 5.

After the legs of the staple have been thus driven through the pad their points, ends or toes are bent toward each other and pressed against the lower or front side of the pad by a clincher mechanism which also may be varied as to details of construction and the form shown in the drawings is therefore to be taken only as an example of an approved form which will serve the present purpose.

As there shown this clincher mechanism comprises two clinching blocks 25, 25 arranged lengthwise end to end within a chamber 26 of a clincher box which latter preferably consists of two side plates 27, 27, two filling pieces 28, 28 arranged between the corresponding ends of the side plates and screws 29, 29 connecting said side plates and filling pieces.

The clincher blocks are pivoted at their outer ends on the side plates by means of horizontal pivot pins 30, 30 so that the inner ends of these blocks can swing vertically. When the legs of the staple emerge from the under side of the pad of the material they engage the clincher blocks which are in their lowered position as shown in Figure 2 and are turned or bent toward each other and thereafter the clincher blocks are raised and operate to press the points or ends of the staple legs against the underside of the pad, as shown in Figure 5. The raising and lowering of the clincher blocks is effected by a T-shaped lifter 31 which is guided in a slot 32 in the lower part of the clincher box and engages with notches 33 formed on the opposing inner sides of the clincher blocks and a vertically movable push rod 34 on which said lifter is mounted.

In the clinching devices as heretofore constructed each block was provided on its upper side or face with a single longitudinal guide groove, the guide grooves of both blocks being in alignment. If therefore the legs of a staple were both driven straight through the pad and engaged the guide grooves of the respective clincher blocks then the ends or points of these legs would be folded, bent or turned properly toward each other into a position parallel and vertically in line

with the longitudinal center of the staple which line is represented by the cross bar of the staple, as shown in Figures 6 and 10. If however one leg of the staple would be diverted from a straight path in penetrating the pad its point or end upon emerging from the underside of the pad may be deflected by the guide groove in the respective block toward the center line of the staple and thus assume an angular position, as shown in Figure 13. In some instances both legs of the staple may be diverted from a straight path through the pad and in the same direction from the center line of the staple in which case both points or ends of the staple may be deflected by the guide grooves of the clincher blocks toward the center line of the staple and thus assume angular positions, as shown in Figure 14. Or the legs of the staple may be diverted in opposite directions from the center line of the staple and their ends or points may be deflected back toward this line by the guide grooves of the clincher block upon emerging from the underside of the pad, as shown in Figure 15. In some instances the points of the legs may miss the guide grooves of the clincher blocks in which case those points would be turned over by the flat surfaces of the block in a more or less twisted form. When the points or ends of the staples are thus arranged in an angular or twisted form relatively to the center line of the staple the work presents an unfinished and defective appearance which is unsatisfactory to the trade and is the cause of rejecting work which is otherwise acceptable.

To avoid this the present invention provides each of the clincher blocks with a plurality of guide channels or grooves which are arranged lengthwise of these blocks and parallel with each other and the grooves in one block being in line with corresponding grooves in the other block. These grooves are preferably of an odd number and comprise a central or main groove and one or more auxiliary grooves on opposite sides of the main groove. In the construction shown in Figures 1, 3, 4, 10, 11 and 12 three of such grooves are shown, a main central groove 35 which is arranged parallel with and immediately below the cross bar or longitudinal center of the staple, and two auxiliary grooves 36, 36, arranged on opposite sides of the main groove and parallel therewith.

If the legs of a staple are driven straight through the pad the points or ends of the same both enter the main central groove 35 and are folded, bent or turned toward each other parallel with each other and the center line of the staple represented by its cross bar, as shown in Figures 6 and 10. If one of the legs should be diverted from a straight path in penetrating the pad, its point or end on emerging from the underside of the pad will

engage the respective auxiliary guide groove 36, as shown in Figure 11, and be bent or turned thereby into a position in which this end is parallel with but off-set from the 5 turned end or point of the other leg of the staple, as shown in Figure 7. If both legs of the staple are diverted away from opposite sides of the center line of the staple the points of the same will engage with the 10 auxiliary guide grooves on opposite sides of the central or main groove, as shown in Figure 12 and then be bent or turned toward each other on the underside of the pad so that the same are off-set but arranged parallel 15 with each other and with the cross bar of the respective staple, as shown in Figure 8. In some instances both legs of the staple may be diverted laterally from the same side of the staple center line in which case the ends 20 of the same upon emerging from the underside of the pad will engage with corresponding auxiliary grooves of both clincher blocks and be turned thereby into a position in which they are in line with each other and 25 parallel with the center line of the staple, as shown in Figure 9.

If desired more than three guide grooves may be employed, for example, as shown in Figure 16, each clincher block may be provided with a main central guide groove 35 and two auxiliary grooves 36 on opposite sides of the main groove.

In order to cause the ends or points of the staples to aline themselves properly in the 35 guide grooves upon entering any portion thereof these grooves are made V-shaped in cross-section, as shown in Figures 4, 10, 11, 12 and 16 so that the sides or walls are inclined and deflect the staple ends toward the 40 center of the respective groove.

The summits or walls between adjacent guide grooves in each clincher block are very

narrow so as to prevent the points of the staple legs from resting thereon, but in order to prevent such summits from presenting 45 too sharp an edge and wearing rapidly these summits are flattened, as best shown at 37 in Figures 1, 4, and 16. In practice it is preferable to make the flat faces on the summits of the walls between the guide grooves no 50 greater in width than about one-third of the width of the grooves at the top thereof, thereby preventing lodgement of the staple ends on such summits and insuring good 55 work.

In all of these several results the ends or points of the staple legs are parallel with each other and the length of the staple thereby maintaining a well finished and satisfactory appearance of the work and increasing 60 its value accordingly.

I claim:

1. A clincher for wire stapling machine provided on its face with a plurality of guide grooves arranged parallel and length-wise of the clincher, each of said grooves being of the same V-shape cross-section throughout its length; and the summit of the walls between adjacent grooves being flat and of the same width throughout the 70 length thereof.

2. A clincher for wire stapling machine provided on its face with a plurality of guide grooves arranged parallel and length-wise of the clincher, each of said grooves being of the same V-shape cross-section throughout its length; and the summit of the walls between adjacent grooves being flat and of the same width throughout the 75 length thereof and of less width than the 80 diameter of the wire of which the staples are made.

In testimony whereof I affix my signature.
HOWARD G. ALLEN.
